UNITED STATES PATENT OFFICE.

MARIE LOUISE BOISVERT, NÉE PINARD, OF MONTREAL, QUEBEC, CANADA.

WRINKLE-REMOVER.

1,356,112.

Specification of Letters Patent. Patented Oct. 19, 1920.

Application filed February 24, 1920. Serial No. 360,808.

To all whom it may concern:

Be it known that I, MARIE LOUISE BOISVERT, née PINARD, residing at 178 Parc Lafontaine, in the city of Montreal, in the 5 Province of Quebec, in the Dominion of Canada, have invented certain new and useful Improvements in Wrinkle-Removers; and I do hereby declare that the following is a full, clear, and exact description of the 10 same.

The present invention relates to improvements in a wrinkle remover and the main object of this invention is to provide a device of this character that will be invisible 15 being concealed in the hair of the wearer as well as being so adapted that it will draw upwardly a fallen facial, thus removing the wrinkles, without any inconvenience whatever to the user.

20 A further object is to provide a device of this character cheap to manufacture, light and particularly easy to apply.

Another object is to provide a device of 25 this character with a buckle and eyelets on the head tapes so that the invention may be easily adjusted to the head.

The invention will be better understood with the aid of the accompanying drawings in which:

30 Figure 1 is a perspective view of the invention, illustrating the buckle and eyelets and hooks forming part of said invention.

Fig. 2 is an illustration of the head of a woman showing how the invention is applied 35 thereto.

Fig. 3 is a plan view in perspective of the buckle locking member.

Fig. 4 is a perspective view of the frame of the buckle.

40 Like numerals of reference indicate corresponding parts in each figure.

In the drawings:—

1 are rectangular pads preferably made of rubber having a surface 2 on which is 45 applied any suitable adhesive composition.

Each of said pads 1 at their upper edge are provided with two slots 3 through which pass the small tapes 4 and 5 respectively. Both ends of the tapes 4 are rigidly secured 50 to the large tapes 6 while the tapes 5 have one end rigidly secured to the said tapes 6, the other end passing through the slot 3, and being provided at its free end 7 with a hook 8 which can be conveniently adjusted 55 by means of the eyelets 9 provided on the tapes 6. Intermediate of said tapes 6 is

a buckle 10 having an horizontal opening 11 and transverse slot 12. The tapes 6 are made to pass through the openings 11 and the slot 12, but it is to be noted that they 60 are previously folded. In the loops 13 provided by the folded tapes 6 after they have been properly arranged in the buckle, the locking member 14 is then inserted in said loops so as to lock the tapes after they have 65 been conveniently adjusted. The buckle has the property of not allowing the tapes 6 to loosen after they have been adjusted, unless the locking member is pulled out of the buckle. 70

Secured under said tapes 6 and under the eyelets 9 are strips 15 to prevent the scalp from coming into contact with the metal eyelets. It will readily be seen that when a suitable adhesive composition is applied 75 on the surface 2 of the pads 1, the device is then made to pass over the top of the head, and the pads 1 are made to adhere to the temples. It is then adjusted over the head by pulling on the ends of the tapes 6, and 80 then, by the tapes 5 by means of the hooks 8 and the eyelets 9 on the large tapes 6. When the device has been properly adjusted the hair may be combed as usual, thus covering the device and rendering it completely 85 invisible.

What I claim as my invention is:—

1. A wrinkle remover of the character described comprising a pair of pads of any suitable material provided with an adhesive 90 surface, two relatively large tapes each provided with a plurality of eyelets, a buckle adapted to secure said tapes together, a small tape secured at each end of said large tape adjoining one edge thereof and adapted to engage adjacent an end of each of said pads, another small tape adapted to engage each of said pads adjacent their other ends provided with a hook adapted to engage said eyelets whereby said pads can be adjusted substantially as described. 95

2. A wrinkle remover of the character described comprising a pair of pads of any suitable material provided with an adhesive surface, two relatively large tapes each provided with a plurality of eyelets suitably distanced from one another, a buckle comprising a hollow member having a transverse slot therein adapted to receive the folded free ends of the large tapes, locking 105 member adapted to engage the folded ends of said tapes, a small tape secured at each 110

end of said large tape adjacent one edge thereof and adapted to engage adjacent one end of said pads, another small tape adapted to engage each of said lugs adjacent their other ends provided with a hook adapted to engage said eyelets in said large tapes whereby said pads can be adjusted substantially as described.

3. A wrinkle remover, in combination
10 with the securing tapes, a buckle comprising
a hollow member having a transverse slot
on one side thereof, said securing tapes

being adapted to pass through said hollow member entering from each end thereof and projecting through said transverse slot 15 and means to lock said tapes in said hollow member substantially as described.

Signed at Montreal, Quebec, Canada, this
25th day of January, 1920.

MARIE LOUISE BOISVERT, NÉE PINARD.
